CONTROL APPARATUS

Lars O. Grondahl, Pittsburgh, and Paul N. Bossart, Cheswick, Pa., assignors to The Union Switch & Signal Company, Swissvale, Pa., a corporation of Pennsylvania

Application October 8, 1941, Serial No. 414,101

12 Claims. (Cl. 246—124)

Our invention relates to control apparatus, and it has particular reference to the organization of such apparatus into control systems for railroads arranged to provide at the given point a warning or indication that a train is approaching such point.

It has been proposed heretofore to provide approach control or indications, in cases where the control or indication required is an essential element of the permanent signal system, by means permanently installed as a portion of the system and usually involving track circuits together with the necessary insulated rail joints. At times, however, it is desirable temporarily to approach control or indicate the approach of a train at a given point, as for example during the time that a construction or maintenance crew is working on a given section of track, or for the period that relatively heavy highway traffic is caused to travel an unprotected crossing, ordinarily handling a small amount of traffic, due to a detour on a main highway. In these latter cases, the expense of installing insulated joints, and the accompanying interference with traffic moving over the track during the insulation of the joints, may not warrant the use of the usual track circuit apparatus for controlling the approach warning or indication devices.

It is an object of our present invention to provide systems involving readily portable and easily installed apparatus arranged to provide an approach control or indication when a train approaches a given point on a trackway, and which systems are an improvement upon those shown in a copending application for Letters Patent of the United States, Serial No. 414,100, filed by us on an even date herewith.

Another object is to provide means arranged to be independent of the usual track circuit apparatus and functioning to provide a warning or indication when a train approaches a given point on a trackway.

An additional object is to provide an approach control system involving readily portable, easily assembled apparatus arranged to avoid the necessity of using line wires or cables extending along the trackway.

A further object is to provide novel and improved approach control and indication systems involving track circuit apparatus arranged to have the range of shunting effectiveness of such apparatus limited by the frequency of the current employed, thus dispensing with the necessity for insulated rail joints ordinarily required to con-

5 fine track circuit current to selected portions of track.

The above-mentioned and other important objects and characteristic features which will become readily apparent from the following description, are attained in accordance with our invention by utilizing a source of high frequency oscillations connected across the rails of a stretch, a relay also connected across the rails adjacent to the connection of the source for energization from the source, another source, a circuit controlled by the relay for connecting one terminal of the other source to a conductor and for connecting the other terminal of the other source to one rail of the stretch, another relay, a warning device controlled by the other relay, and means connected across the conductor and the one track rail, at a point remote from the first relay, for energizing the other relay from the other source.

We shall describe several forms of apparatus embodying our invention, and shall then point out the novel features thereof in claims.

In the accompanying drawing, Fig. 1 is a diagrammatic view showing one form of apparatus embodying our invention. Fig. 2 is a diagrammatic view illustrating a modified form of the apparatus represented in Fig. 1, and also embodying our invention. Fig. 3 is a diagrammatic view illustrating a modification of a portion of the apparatus represented in Fig. 2, and also embodying our invention. In each of the several views, similar reference characters have been employed to designate corresponding parts.

Referring to Fig. 1, the reference character X designates a stretch of railway track over which traffic normally moves in the direction indicated by an arrow or from left to right as viewed in the drawing. A source of high frequency current, such as an oscillator 5, has its output terminals connected across the rails 1 and 1a of the stretch, and a relay, designated by the reference character TR, is connected, in multiple with the rails 1 and 1a, to the output terminals of oscillator 5 through a rectifier 6. The parts are so proportioned and adjusted that relay TR normally is energized and picked up, but when a train approaches within a relatively short distance of, say, 100 feet from the connection of the oscillator to the track rails, the shunt established through the wheels and axles of the train causes the current in relay TR to drop to a value below that required to hold up relay TR, whereupon that relay releases. After the train passes beyond the effective shunting range, relay TR of course picks

up. The frequency of current supplied from oscillator 5 preferably is within the range of, say, 20,000 to 200,000 cycles per second. This high frequency current has a rather high attenuation in the track rails, hence the shunting effectiveness of a train may be limited to relatively low distances of the order of 100 feet without requiring the use of the usual insulated rail joints normally employed to limit track circuit currents to selected portions of a track.

Relay TR connects a suitable source of current, such as a battery 7, in a track circuit comprising one rail 1 of the track and a conductor. The conductor may, as indicated in the drawing, comprise an earth or ground path having a ground terminal G1.

A relay R is connected across rail 1 and the conductor at the point at which it is desired to provide an indication of an approaching train. The connection of relay R is arranged on the 20 stick circuit principle to include its own front contact 8, and an acknowledging switch AS is connected across front contact 8 of relay R. Relay R controls an indicator device K over an obvious circuit including back contact 9 of relay R and a suitable source of current, such as a battery 10.

In the normal condition of the apparatus, as represented in the drawing, relay R is energized over its stick circuit by current supplied from battery 7 and transmitted to relay R through the track circuit comprising rail 1 and the conductor. When, however, a train shunt causes relay TR to release, then battery 7 is disconnected from relay R and that relay in turn releases to energize indicator K. Acknowledging switch AS may now be closed, but relay R of course remains released until the train passes beyond the effective shunting distance of the high frequency track circuit including relay TR. When this happens, relay TR picks up, and connects battery 7 in circuit with relay R to cause the latter relay in turn to pick up and open its back contact 9 and close its front contact 8. Indicator K thereupon becomes deenergized, and acknowledging switch AS may be opened to restore the apparatus to its normal condition.

From the foregoing, it is apparent that we have provided an approach indication or control system controlled by a train shunttable track circuit arranged to have an effective shunting range defined not by the usual rail joints but by the frequency of track circuit current employed. This track circuit apparatus is employed to control an approach relay disposed at a point remote from the track circuit apparatus, and which approach relay is energized over a non-train-shunttable track circuit which involves no line wires or cables extending along the track. The circuit of the approach relay R is arranged to have as its two transmission conductors a track rail and another conductor such as a ground path. It is, of course, to be noted that in the event that our invention is applied to a stretch of multiple track railroad, a rail of the second track of such road may be employed as the conductor in the place of the ground path represented in Fig. 1.

In Fig. 2, we have represented the apparatus illustrated in Fig. 1 modified for use in connection with a stretch of railroad over which trains operate in either direction, and which apparatus is arranged to provide an indication whenever a train approaches a given point. Referring to Fig. 2, we have represented at D in the drawing, apparatus arranged to cause an indication to be

displayed at a remote given point, such as at E, when an eastbound train, operating from left to right as viewed in the drawing, approaches location D. At F we have represented other apparatus arranged to cause an indication to be displayed at E when a westbound train approaches point F.

The apparatus at point D comprises a first track relay TR1 connected through rectifier 6 to the track rails 1 and 1a; an oscillator 5 energized from a suitable source, such as a battery 12, and having its output terminals connected through a circuit including a resistor 13 across the rails 1 and 1a at a point intermediate E and the connection of relay TR1 to the track rails; and two other track relays TR2 and TR3 separately connected across the track rails, each through a rectifier 6, at points intermediate E and the connection of oscillator 5 to the track rails. Each relay TR2 and TR3, as indicated in the drawing, is provided with contact arrangements of the continuity-transfer type arranged in such manner that when deenergized, each relay closes its back contact prior to opening its front contact, and likewise when each relay becomes energized its front contact is closed before its back contact opens. A suitable source of current, such as a generator designated by the reference character f1, has one of its output terminals connected to a conductor, which may comprise a ground path having a ground terminal G1, and has its other terminal normally connected to rail 1 of the stretch over a circuit which extends from generator f1, through front contacts 14, 15 and 16 of relays TR1, TR2 and TR3, respectively.

An auxiliary relay, designated by the reference character AR, is provided for at times connecting the other output terminal of the source f1 to rail 1 over an alternate circuit path completed at front contact 17 of relay AR. Relay AR is controlled by relays TR1, TR2 and TR3 in a manner to be made clear presently.

At the location, E, where it is desired to provide an approach indication, a relay R1 is provided and is coupled to rail 1 and the conductor by means comprising a transformer 18 and a resonant rectifier unit TU1. Transformer 18 has its primary winding 19 connected across rail 1 and the conductor, and has its secondary winding 20 connected through unit TU1 to the winding of relay R1. The details of construction of the resonant rectifier unit TU1 are not shown in the drawing since such units are well known in the art, and usually comprise a rectifier and a reactor condenser tuning unit tuned to resonance at a frequency corresponding to the frequency of current supplied from the source f1. The connection of relay R1 to unit TU1 preferably is arranged on the stick circuit principle to include a front contact 21 of relay R1, as can be seen from an inspection of the drawing, and an acknowledging switch AS is provided for at times completing an alternate path around front contact 21 of relay R1 in the circuit connection of the relay to unit TU1. Relay R1 controls an indicator device K over an obvious circuit including back contact 22 and a source of current, such as a battery 23.

The apparatus at E also includes another relay R2 having a function and arranged in a manner to be made clear presently, to be selectively responsive to current supplied to rail 1 and the conductor by apparatus located at point F and hereinafter described.

The apparatus at D is in its normal condition, as represented in Fig. 2, when the track adjacent to point D is unoccupied by a train. In this condition of the apparatus, relays TR1, TR2 and TR3 are energized, and the source f_1 is connected across the ground electrode G1 and rail 1 over the previously traced circuit including a front contact of each of the track relays. Relay R1 at E is picked up, and its front contact 21 is closed so that relay R1 is energized by current supplied from source f_1 . Indicator K accordingly is deenergized.

Relays TR1 and TR2 are connected at D to the rails of stretch X, on opposite sides of the connection of oscillator 5 to the rails, at distances from the oscillator connection selected to enable a train operating on the track to shunt and cause the first encountered one of such relays to be released prior to causing the release of the second relay. If, as has been assumed heretofore, current having a frequency in the range of 20,000 to 200,000 cycles per second is supplied from oscillator 5, the effective limits of such current, due to the relatively high attenuation in the track rails, is of the order of 50 to 100 feet, hence the relays TR1 and TR2 are preferably spaced apart an appropriate distance of, say, 100 feet. Relay TR3 is employed as a checking relay, as will be made clear presently, and relays TR2 and TR3, although separately connected to the rails, are connected to the rails relatively close to each other so that both relays will be substantially simultaneously shunted and released by a train on the stretch.

When an eastbound train approaches D, and comes within the effective shunting range of relay TR1, that relay is shunted and releases to open its front contact 14 and thus interrupt the circuit connection of source f_1 to rail 1. Relay R1 at E accordingly becomes deenergized, and releases to open its front contact 21 and close its back contact 22 to energize indicator K. An indication is thus provided at E when an eastbound train arrives at D and shunts relay TR1.

Relays TR2 and TR3 are released by the eastbound train proceeding toward point E, and when back contacts 25 and 26 of relays TR2 and TR3, respectively, close, relay AR becomes energized over a circuit extending from one terminal of rectifier 27 through back contact 26 of relay TR3, back contact 25 of relay TR2, back contact 28 of relay AR, resistor 29, and the winding of relay AR to the other terminal of rectifier 27. Rectifier 27 has its input terminals connected across the terminals of resistor 13 and hence rectifier 27 is energized from a source of potential obtained from the voltage drop across such resistor. Relay AR has a condenser 30 connected across its terminals, and this condenser becomes charged in multiple with the winding of relay AR. The circuit of relay AR includes its own back contact 28, hence relay AR interrupts its own energizing circuit at its back contact 28 when the relay picks up. When this happens, condenser 30 discharges through relay AR to maintain the relay in its picked-up position for an appreciable interval, say for approximately one or two seconds. After condenser 30 discharges, relay AR releases and its previously traced circuit is completed at back contact 28, whereupon relay AR becomes energized, and condenser 30 becomes charged. Relay AR again picks up to open its energizing circuit, condenser 30 again discharges through the relay, and relay AR again releases to recomplete its energizing circuit. This cycle of operation of relay AR is maintained until relays TR2 and TR3 pick up

due to the passage of an eastbound train and removal of its train shunt.

By properly proportioning the parts of relay AR, resistor 29 and condenser 30, relay AR may be caused, during the just described cycle of operation of the relay, to occupy its picked-up position for intervals of time considerably longer than the intervals during which the relay is released. For example, each time relay AR picks up, it may be maintained in its picked-up position for approximately two seconds, whereas each time the relay releases, it remains released only a fraction of a second. Each time that relay AR picks up, its front contact 17 closes to complete the previously mentioned alternate circuit, including that contact, over which source f_1 is connected to rail 1.

During the interval relay AR is caused to pick up and release cyclically, energy from source f_1 is intermittently applied across rail 1 and the ground return path. This energy, however, may have no useful function at this time since relay R1 was caused to release when relay TR1 became shunted, and relay R1 in releasing opened its front contact 21 to interrupt its stick circuit over which such relay normally is energized. Relay R1 accordingly may be picked up only when acknowledging switch AS is closed and energy is impressed from source f_1 across rail 1 and the ground.

It is contemplated that the apparatus represented in Fig. 2 will be employed to warn maintenance or construction crews working on the track adjacent to point E that a train is approaching, and it is further contemplated that the warning should be exhibited until the approaching train has passed the work location. Thus, the supervisor or foreman of the track crew would be authorized to operate acknowledging switch AS only after the train has cleared the point at which his crew is working. When this happens, relays TR1, TR2 and TR3 of course will be picked up, and the source f_1 will be constantly connected to rail 1 so that when acknowledging switch AS is closed, relay R1 becomes energized to deenergize indicator K and to complete its previously traced stick circuit.

The above described cyclic operation of relay AR, and consequent intermittent impression of energy from source f_1 across rail 1 and the ground, has a useful function when a westbound train operates along the stretch. This westbound train will cause, in a manner to be made clear presently, an indication to be provided at E when the train nears point F. When such train approaches point D, relays TR3 and TR2 are shunted and release simultaneously. When relays TR3 and TR2 release, their back contacts 26 and 25 close before their front contacts 15 and 16 open, hence before source f_1 is disconnected from rail 1 at front contact 15 or 16 of relay TR2 and TR3, relay AR is caused to become energized, and relay AR accordingly picks up to close its front contact 17 and complete the alternate circuit connection of source f_1 to rail 1. Relay AR is caused to pick up and release cyclically in the manner described in detail hereinbefore, and relay R1 at E is intermittently energized by current supplied to the relay during the intervals that relay AR is picked up. Relay R1 has slow releasing characteristics selected to maintain that relay in its energized position during the relatively short intervals that relay AR is released, hence relay R1 is maintained in its picked-up position to maintain indicator K deenergized. It follows, therefore, that when a westbound train operates on the stretch, the apparatus at D functions to maintain relay

R1 energized and indicator K accordingly is not energized.

Track relay TR1 of course is shunted by the westbound train, and relay TR1 closes its back contact 32 to prepare an alternate stick circuit path for relay AR. This circuit becomes completed when relay TR3 picks up due to the removal of the train shunt. When relay TR3 picks up, its front contact 33 closes prior to the opening of its back contact 26, and relay AR thereupon becomes energized over a circuit extending from one output terminal of rectifier 27 through front contact 33 of relay TR3, front contact 34 of relay AR, back contact 32 of relay TR1 and the winding of relay AR to the other terminal of rectifier 27. This circuit holds relay AR in its picked-up position to maintain source f1 connected to rail 1 during the interval required, after relay TR3 picks up, for the train to remove its shunt from relay TR1. When relay TR1 picks up, source f1 is connected to rail 1 over its previously traced circuit including a front contact of each of the track relays. Also, relay AR becomes deenergized, and the apparatus at D is restored to its normal condition.

It is to be noted that two separately connected track relays TR2 and TR3 are employed at point D. These relays are arranged to be simultaneously shunted, and both relays are required to release in order to energize relay AR and thus intermittently connect source f1 to rail 1 over front contact 17 of relay AR. The use of two relays in this manner provides protection against an improper condition in the apparatus which might be caused by an accidental disconnection of a track relay from the track rails. That is to say, should relay TR1 become accidentally disconnected from the track rails, the apparatus at D would function to release relay R1 at E. A circuit failure or open connection of this relay accordingly would cause the apparatus to fail safe, that is, it causes a warning indication to be provided, and by a continued display of this warning, furnishes an indication that an improper condition exists and enables the proper steps to be taken to restore the circuit connection of relay TR1. If, however, only one of the two relays TR2 and TR3 is employed to control the auxiliary relay AR, and such track relay becomes disconnected or its circuit connection fails, then such relay would cause relay AR to be energized, and thus relay R1 to be intermittently energized to prevent energization of indicator K when an eastbound train subsequently shunts relay TR1. This dangerous condition is obviated by employing two separately connected track relays to control relay AR, thus requiring a simultaneous failure in the circuits of both relays before a dangerous condition of the apparatus can be established.

It should also be noted that auxiliary relay AR is energized from a source of potential derived from the voltage drop across resistor 13 interposed in the connection of oscillator 5 to the track rails. This arrangement insures that relay AR cannot become energized should the oscillator become disconnected from the track rails, and hence avoid the possibility of maintaining relay RE energized over a front contact of relay AR should the track circuit apparatus be rendered ineffective due to a failure of either the source or its connection to the track rails.

The apparatus at point F substantially corresponds to the apparatus at point D, with the exception that the source of current, connected at

F to rail 1 and the ground terminal G1, has characteristics distinctively different from the characteristics of current supplied at D to the same rail and ground. The source of current at F may, for example, be unidirectional in character, or as shown may comprise a generator f2 of alternating current having a frequency distinctively different from the frequency of current supplied from generator f1 at D. At E, a resonant rectifier unit TU2, tuned to resonance at a frequency corresponding to the frequency of current from generator f2, is connected to secondary winding 20 of transformer 18 and has its output terminals connected to relay R2 over front contact 36 of that relay. Acknowledging switch AS is provided for relay R2, and an indicator K1 is energized over back contact 37 of relay R2.

Another difference in the apparatus at F comprises the provision of a condenser 38 and a resistor 39 connected between the heel of contact 28 and one terminal of the winding of such relay. The capacity of this condenser and the value of resistor 39 are so proportioned that enough energy is stored in the condenser when relay AR is picked up, that when the relay releases, the charge on the condenser, discharging through back contact 28 and the winding of relay AR and condenser 38, causes relay AR again to become picked up and hold up for an interval of the order of, say, four seconds, or for an interval longer than that required for the train to clear relay TR1 after having removed its shunt on relays TR2 and TR3. This condenser arrangement replaces the stick circuit path previously traced in the apparatus at D for relay AR, and thus obviates the possibility of a dangerous condition existing in the apparatus should relay TR1 fail to pick up due to an open circuit connection in its circuit. Thus, for example, should relay TR1 at D fail to pick up after a westbound train clears the location, the relay would remain down and relay AR would be maintained energized over its stick circuit, to maintain generator f1 connected to rail 1. An eastbound train reaching point D would, therefore, not cause an indication to be displayed at E.

The arrangement of the apparatus at F precludes this possibility since if relay TR1 at F does fail to pick up it cannot maintain relay AR energized and such failure would not cause relay R2 at E to be maintained energized. A failure would be detected, however, due to the fact that when relay AR does release after the discharge of condenser 38, the normal circuit over which generator f2 is connected to rail 1 cannot be completed at front contact 14 of relay TR1, and the continued energization of indicator K1 when no train occupies the stretch provides a means of indicating that the apparatus at F is in an improper condition.

In Fig. 3 we have represented apparatus adapted to be employed at point E of Fig. 2, and arranged to modify the system shown in Fig. 2 so as to terminate the energization of the indication displayed at E automatically when the train clears such point. Referring now to Fig. 3, the apparatus represented at E comprises two control relays R1 and R2, as represented in Fig. 2, connected across rail 1 and the conductor through a transformer 18 and resonant rectifier units TU1 and TU2, respectively. Each relay is connected to its associated resonant rectifier unit over its own front contact, and hence such connection involves the stick circuit principle. A single indicator or warning device K is energized whenever

either or both relays R1 and R2 closes its back contact 22 or 37, respectively.

The apparatus at E further comprises an oscillator 5 which has its output terminals connected at E to the rails 1 and 1a, and two relays TR4 and TR5 connected, in multiple, across the output terminals of oscillator 5, each through rectifier 6. Relay TR4 is quick acting, while relay TR5 is slow acting and has associated therewith a condenser 42 and a resistor 43 arranged to assist in providing such slow acting characteristics. Relays TR4 and TR5 are normally energized, and are arranged to control a pick-up circuit for control relays R1 and R2.

The apparatus of Fig. 3 functions in the following manner: Assume that an eastbound train operating on stretch X causes the apparatus at D in Fig. 2 to disconnect source 11 from its associated track circuit. Relay R1 at E of Fig. 3 accordingly is caused to release, and indicator K becomes energized. As pointed out hereinbefore, energy is applied to the track circuit of relay R1 when the train passes point D, but since the circuit of relay R1 is open at its front contact 21, relay R1 remains released.

When the train approaches point E of Fig. 3, relays TR4 and TR5 become shunted and are caused to release. Relay TR4 releases prior to relay TR5, due to the slow acting characteristics of the latter relay, and at this time no useful function is served by such relays, except that if desired, an indicator 44 may be provided and energized at this time over an obvious circuit including front contact 45 of relay TR5, back contact 46 of relay TR4 and the operating element or filament of indicator 44. This indicator may be desirable to indicate that a train has reached point E.

After the train passes point E and removes its shunt from relays TR4 and TR5, relay TR4 picks up prior to relay TR5, again due to the slow acting characteristics of the latter relay. When relay TR4 picks up, a pick-up circuit path is then completed, through front contact 47 of relay TR4 and back contact 48 of relay TR5, around front contact 21 of relay R1. Relay R1 accordingly becomes energized over its pick-up circuit during the slow pick-up interval of relay TR5, and relay R1 picks up to close its front contact 21 to complete its stick circuit path, which path holds relay R1 energized after relay TR5 picks up. Relay R1 also opens its back contact 22 to deenergize indicator K. It follows, therefore, that indicator K of Fig. 3 may be energized when an eastbound train shunts the apparatus represented at point D in Fig. 2, and may be caused to become deenergized automatically when the eastbound train clears point E. The apparatus at E will, when applied to a highway crossing signal installation, be located adjacent to the highway intersection and indicator K in such event will comprise a highway crossing signal of any suitable form.

After relay TR5 picks up at the end of its slow pick-up interval, the apparatus at E is restored to its normal condition as represented in the drawing.

When relay TR4 is picked up and relay TR5 is released, these relays provide a pick-up circuit path for relay R2 around its front contact 36, as is readily apparent from an inspection of the drawing, hence it follows that when a westbound train operates over the stretch and causes indicator K to be energized in the manner described

in detail in connection with the apparatus of Fig. 2, relay R2 at E is energized and indicator K is caused to become deenergized automatically when the westbound train clears the apparatus at E.

From the foregoing description of the apparatus represented in Fig. 3, it is apparent that we have provided means adapted to be incorporated into the apparatus employed in Fig. 2 and capable of modifying the apparatus represented in Fig. 2 for use in controlling highway crossing signals. Such a highway crossing signal system is arranged for use to provide protection temporarily at crossings where such protection ordinarily is not required but may be required for a short interval not justifying the expense and trouble involved in installing the usual rail joints required for the usual crossing signal systems.

Although we have herein shown and described only a few forms of control apparatus embodying our invention, it is understood that various changes and modifications may be made therein within the scope of the appended claims without departing from the spirit and scope of our invention.

Having thus described our invention, what we claim is:

1. In combination, a stretch of railway track comprising electrically continuous track rails, a source of high frequency oscillations of the order of 20,000 cycles per second connected across the rails of said stretch, a relay also connected across said rails adjacent to the connection of said high frequency source for energization from that source, another source, a circuit controlled by said relay for connecting one terminal of said other source to a conductor and for connecting the other terminal of said other source to one rail of said stretch, another relay, a warning device controlled by said other relay, and means connected across said conductor and said one track rail, at a point remote from said first relay, for energizing said other relay from said other source.

2. In combination, a stretch of railway track comprising electrically continuous track rails, a source of high frequency oscillations of the order of 20,000 cycles per second connected across the rails of said stretch, a relay also connected across said rails adjacent to the connection of said high frequency source for energization from that source, another source, a circuit controlled by said relay for connecting one terminal of said other source to a conductor and for connecting the other terminal of said other source to one rail of said stretch, another relay, a warning device controlled by said other relay, and means for coupling said other relay across said conductor and said one rail at a point remote from said first relay.

3. In combination, a stretch of railway track comprising electrically continuous track rails, a source of high frequency oscillations within the range of 20,000 to 200,000 cycles per second connected across the rails of said stretch, a relay also connected across the rails adjacent to the connection of said source for energization from said source, another relay having one terminal connected to one rail of said stretch at a point remote from said first relay, a warning device controlled by said other relay, another source, and means controlled by said first relay for connecting one terminal of said other source to the said one rail and having its other terminal connected in circuit to the other terminal of the winding of

said other relay through circuit means not involving the other rail of said stretch.

4. In combination, a stretch of railway track comprising electrically continuous track rails, two track relays connected across the rails of said track, a source of high frequency oscillations ranging above 20,000 cycles per second so as to have an extremely high attenuation in the track rails connected to said rails at a point intermediate the connection of said relays to said rails, a source of current connected over a front contact of each of said relays to one rail of said track and to a conductor, another relay coupled at a remote point across said one rail and said conductor, and means controlled by one of said track relays for intermittently connecting said current source across said one rail and said conductor.

5. In combination, a stretch of railway track comprising electrically continuous track rails, two track relays connected at spaced points across the rails of said track, a source of high frequency oscillations of the order of 20,000 cycles per second connected to said rails at a point intermediate the connections of said track relays to said rails, a source of current, another relay at a point remote from said current source, means controlled by front contacts of each of said track relays for energizing said other relay from said current source over a circuit including a front contact of said other relay, means controlled by the one track relay nearer to said other relay for at times maintaining said other relay energized from said current source when the most remote track relay is released, and a warning device controlled by said other relay.

6. In combination, a stretch of railway track having electrically continuous track rails, a source of high frequency oscillations within the range of 20,000 to 200,000 cycles per second connected across said rails adjacent to the connection of said across the rails of said track, two track relays connected across said rails adjacent to the connection of said source for energization therefrom and arranged to be simultaneously shunted by a train in said stretch, one of said relays having slow response characteristics, a control relay controlled from a remote point over a circuit including its own front contact, and a pick-up circuit for said control relay including a back contact of said slow pick-up track relay and a front contact of the other of said track relays.

7. In combination, a stretch of railway track having electrically continuous track rails, a source of oscillations in the 20,000 to 200,000 cycles per second band connected across the rails of said track, two track relays connected across said rails adjacent to the connection of said source for energization therefrom and arranged to be simultaneously shunted by a train in said stretch, one of said relays having slow response characteristics, and an indication device controlled over a circuit including a front contact of said slow response relay and a back contact of the other relay.

8. In combination, a stretch of railway track having electrically continuous track rails, a high frequency oscillator for generating current within the 20,000 to 200,000 cycles per second band and connected across the rails of said track, two track relays connected across said rails adjacent to the connection of said oscillator for energization therefrom and arranged to be simultaneously shunted by a train in said stretch, one of said relays having slow response characteristics, and

means for governing an indicator device over a circuit including a back contact of said slow response relay and a front contact of the other relay.

5 9. In combination with a stretch of railway track comprising electrically continuous track rails, two track relays connected across the rails of said track at spaced points, a high frequency oscillator for generating a current having a frequency in the 20,000 to 200,000 cycles per second band and connected to said rails at a point intermediate the connection of said track relays to said rails for energizing said track relays, a source of current, a slow releasing control relay associated with said track at a point remote from said source, means controlled by front contacts of each of said track relays for energizing said control relay from said source over a rail of said track and a conductor not comprising a rail of said track, a device controlled by said control relay, an auxiliary slow release relay having a condenser connected in multiple with its winding, means for energizing said auxiliary relay over a circuit including its own back contact and a back

25 contact of the track relay nearer to said control relay, and means controlled by said auxiliary relay when picked up for intermittently connecting said source in circuit with said control relay for intervals of time separated from each other by other intervals shorter in duration than the release interval of said control relay.

10. In combination with a stretch of railway track having electrically continuous track rails, two track relays connected across the rails of said track at spaced points, a high frequency oscillator connected through a resistor to said rails at a point intermediate the connections of said track relays to said rails, said oscillator generating current having a frequency within the range

35 of 20,000 to 200,000 cycles per second and said track relays arranged to be energized by current supplied from said oscillator, a source of current, a slow releasing control relay associated with said track at a point remote from said source, means controlled by front contacts of said track relays for energizing said control relay from said source over a rail of said track and a conductor not comprising a rail of said track, a device controlled by said control relay,

40 15. an auxiliary slow release relay having a condenser connected in multiple with its winding, means for energizing said auxiliary relay from a source of potential obtained by the voltage drop across said resistor and over a circuit including its own back contact and a back contact of the track relay nearer to said control relay, and means controlled by said auxiliary relay when picked up for intermittently connecting said source in circuit with said control relay for intervals of time separated from each other by other intervals shorter in duration than the release interval of said control relay.

11. In combination with a stretch of railway track having electrically continuous track relays, a high frequency oscillator connected across the rails of said stretch for impressing thereon current having a frequency within the range of 20,000 to 200,000 cycles per second, two track relays connected across the rails on opposite sides of the oscillator connections for energization from said oscillator, a slow releasing control relay associated with said track at a point remote from said oscillator, a source of current, means controlled by front contacts of each of said track relays for connecting said source in circuit with said

control relay, a device governed by said control relay, an auxiliary slow release relay having an energy storing device connected across its terminals, means for energizing said auxiliary relay over a circuit including its own back contact and a back contact of the one of said two track relays nearer to the control relay, other means for energizing said auxiliary relay over a circuit including its own front contact and a front contact of said one track relay as well as a back contact of the other of said track relays, and means controlled by said auxiliary relay for maintaining said control relay in its energized position in the event that a train shunts said one track relay prior to shunting the other track relay.

12. In combination with a stretch of railway track having electrically continuously track rails, a high frequency oscillator connected across the rails of said stretch for impressing thereon current having a frequency within the range of 20,000 to 200,000 cycles per second, two track relays connected across the rails on opposite sides of the

5 oscillator connections for energization from said oscillator, a slow releasing control relay associated with said track at a point remote from said oscillator, a source of current, means controlled by front contacts of each of said track relays for connecting said source in circuit with said control relay, a device governed by said control relay, an auxiliary slow release relay having an energy storing device connected across its terminals, 10 means for energizing said auxiliary relay over a circuit including its own back contact and a back contact of the one of said two track relays nearer to the control relay, a condenser charged in multiple with the winding of said auxiliary relay and discharging through said auxiliary relay upon release of such relay, and means controlled by 15 said auxiliary relay for maintaining said control relay in its energized position in the event that a train shunts said one track relay prior to shunting the other track relay.

LARS O. GRONDAHL.
PAUL N. BOSSART.

CERTIFICATE OF CORRECTION.

Patent No. 2,346,749.

April 18, 1944.

LARS O. GRONDAHL, ET AL.

It is hereby certified that error appears in the printed specification of the above numbered patent requiring correction as follows: Page 6, first column, line 41, claim 6, strike out "across said rails adjacent to the connection of said"; and second column, line 45, claim 10, after "of" insert --each of--; line 64, claim 11, for "relays" read --rails--; and that the said Letters Patent should be read with this correction therein that the same may conform to the record of the case in the Patent Office.

Signed and sealed this 6th day of June, A. D. 1944.

Leslie Frazer
